LAZY SUSAN RACK STAND FOR SUPPORTING PACKS OF PLAYING CARDS AND A SCORE PAD

Jerome G. Caplan, Fairfield, Conn.

Application January 13, 1956, Serial No. 39,741

Term of patent 3½ years

(Cl. D34—13)

Fig. 1 is a front elevation of the Lazy Susan rack stand for supporting packs of playing cards and a score pad, showing my new design;

Fig. 2 is a side elevation;

Fig. 3 is a top plan view; and

Fig. 4 is a bottom plan view.

I claim:

The ornamental design for a Lazy Susan rack stand for supporting packs of playing cards and a score pad, substantially as shown.
